Primary Examiner — Mary Shannon Malley(74) *Attorney, Agent, or Firm* — McAndrews Held & Malloy, Ltd(57) **CLAIM**

The ornamental design for an ANALYTE SENSOR INSERTER, as shown and described.

DESCRIPTION

FIG. 1 is a top perspective view of an ANALYTE SENSOR INSERTER showing our new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom perspective view thereof;

FIG. 9 is a top perspective view of an ANALYTE SENSOR INSERTER showing our new design according to a second embodiment;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a bottom perspective view thereof.

The dashed broken lines in the figures illustrate portions of the ANALYTE SENSOR INSERTER that form no part of the claimed design.
